UNITED STATES PATENT OFFICE.

BENJAMIN ROSENBERG, OF NEW YORK, N. Y.

SHOE-HEEL.

1,049,271.

Specification of Letters Patent. Patented Dec. 31, 1912.

Application filed July 5, 1912. Serial No. 707,708.

To all whom it may concern:

Be it known that I, BENJAMIN ROSENBERG, a citizen of the United States, and a resident of the city of New York, borough 5 of Brooklyn, in the county of Kings and State of New York, have invented a new and Improved Shoe-Heel, of which the following is a full, clear, and exact description.

Among the principal objects which the 10 present invention has in view are: to provide a cushion section for a shoe heel and a wearing surface therefor rigidly secured thereto; to provide a heel of the character set forth with a felt section, leather-covered 15 to harmonize the appearance of said section with the shoe upper and the wearing lifts with which the heel is provided; and to provide efficient means for uniting said felt section and the body of the shoe. 20 Reference is to be had to the accompanying drawings forming a part of this specification, in which similar characters of reference indicate corresponding parts in all the views, and in which— 25 Figure 1 is a detail view in perspective, showing the felt cushion section with which the present heel is provided; Fig. 2 is a detail view in perspective, showing the intermediate leather heel lift, together with an 30 angle-plate for joining said cushion section and intermediate lift; Fig. 3 is a detail view in perspective, showing the bottom or wearing heel lift having a fastening heel-connecting plate; Fig. 4 is a vertical longitudinal 35 section of a heel and a fragment of the shank and sole of a shoe to which the heel is attached; and Fig. 5 is a detail view, in plan, looking from beneath the felt section, to show the recessed bores therein. 40 As seen best in Fig. 4 of the drawings, the heel, when constructed in accordance with the present invention, primarily consists in a thickened felt cushion section 10, a soft leather attaching lift 11, and a hard 45 leather wearing lift 12. The cushion section 10 is preferably constructed from mediumly dense felt, shaped as a solid block, substantially shown in the drawings to conform with the shape of the body portion of 50 the usual shoe heel.

Adjacent the outer edge of the section 10, it is vertically bored to form tubular pockets 13. The pockets 13 extend partially through the section 10. The remaining

portion of said section from the bottom of 55 the pockets 13 is provided with perforations 14, smaller in diameter than the bore of the pockets 13, to form at the bottom of said pockets a shoulder, upon which rests the head 15 of a clenching tubular eyelet fastener 16.

To protect the section 10, and to harmonize the appearance of the same with the leather lifts 11 and 12 and the sole 17 of the shoe, I cover the vertical or exposed 60 edge of the section 10 by a thin flexible leather covering 18. The edge of the covering 18, as shown best in Fig. 4 of the drawings, is turned over the top and bottom of the section 10 to avoid being rubbed or 65 scuffed from the section 10. Any suitable means for uniting the covering 18 and the section 10 may be employed.

Prior to applying the covering 18, the section 10 is equipped with a reinforcing corner plate 19. The corner plate 19 is provided with spurs 20 extended from the vertical wall thereof to engagingly sink into the body of the section 10. Vertically disposed spurs 21 on said plate engage the material of the section 10 from beneath. The plate 19 is also provided with means similar to the spurs 21 extended from the under side of the horizontal flange of said plate, to fasten upon the lift 11. The lift 11 is formed 80 from skived leather to provide a softened surface to adhere to the somewhat similar surface of the section 10. The lift 12 is constructed from hard sole leather; and is preferably provided with a connecting plate 22. 85 The plate 22 has extended from both sides thereof spurs 23. Certain of said spurs are driven into and engage the lift 12, while others engage the lift 11 when the two lifts are joined. 90

To furnish a shoe with a heel constructed in accordance with the present invention, the following method is adopted:—The sole 17 is provided with perforations to receive the shank of the fastener 16. The borings 100 formed in the sole 17 register with the perforations 14 in the section 10. The section 10 is spread with a suitable cement, and then adjusted to the sole 17. The fasteners 16 are entered through the pockets 13, and 105 the shanks are extended through the perforations 14 in the section 10 and the corresponding borings referred to as being pro-

vided in the sole 17. The heads 15 of the fasteners 16 rest firmly on the shoulder formed in the pockets 13, and the ends of the shanks of the fasteners 16 are bent over 5 to clench upon the sole 17. When all the fasteners are in place, it will be found that the section 10 is held rigidly secured to the sole 17. The lift 11 is now set, the contacting surfaces of said lift being liberally 10 spread with suitable cement adapted to adhere to the surface of the section 10. The exposed spurs of the plate 19 are forced into the lift 11, thereby aiding in securing said lift in position. The lift 12 is now super- 15 posed upon the lift 11, the exposed spurs 23 of the plate 22 entering the lift 11, which, in conjunction with a suitable cement previously applied to the butted surfaces of the lifts, unites the same. In this position, if 20 such be desired, the lifts 11 and 12 and the section 10 may be united by driving in suitable brads or pegs, care being exercised to avoid the plates 19 and 22.

When a shoe is provided with a cushion 25 section similar to the section 10, it will be found that the action due to the striking of the heel upon the hard pavement is avoided. It also will be found that the pockets 13 operate by the contraction and expansion of 30 the felt forming the section 10 to expel the air normally contained in said pockets through the tubular center of the shank of the fastener 16 into the body of the shoe. When, in the operation of walking, the heel 35 is lifted, the felt of the section 10 expands, the pockets 13 causing the same to draw in air from the body of the shoe through the tubular shanks of the fasteners 16. By means of this action, it will be seen that 40 there is maintained within the shoe a circulation of air very agreeable to the wearer.

Where, in the present specification and claims, the term "lift" has been employed, it will be understood to indicate a single 45 layer of leather usually employed in building up a shoe heel.

Having thus described my invention, I

claim as new and desire to secure by Letters Patent:

1. A shoe heel comprising a resilient body 50 section having formed therein a series of vertically-disposed pockets extending from the lower face of said section part way therethrough; perforations extending from the upper ends of said pockets to the upper 55 face of said section, said perforations being of smaller diameter than said pockets, whereby a shoulder is formed at the upper end of each pocket; a plurality of fasteners for uniting the sole of a shoe and said body 60 section, said fasteners having heads adapted to engage said shoulders and open-ended tubular shanks adapted to extend through said perforations, the ends of said shanks remote from said heads being adapted to be 65 overturned upon the upper surface of said sole; a plurality of leather lifts covering the under side of said section, the inner lift being constructed from relatively soft leather, and the outer lift being constructed from 70 relatively hard leather; and a leather casing for said section.

2. A shoe heel comprising a resilient body section having formed therein a series of vertically-disposed pockets extending from 75 the lower face of said section part way therethrough; perforations extending from the upper ends of said pockets to the upper face of said section, said perforations being of smaller diameter than said pockets, 80 whereby a shoulder is formed at the upper end of each pocket; a plurality of fasteners for uniting the sole of a shoe and said body section, said fasteners having heads adapted to engage said shoulders and a leather cas- 85 ing for said body section.

In testimony whereof I have signed my name to this specification in the presence of two subscribing witnesses.

BENJAMIN ROSENBERG.
